UNITED STATES PATENT OFFICE.

STEPHEN L. PALMER, OF TEANECK, NEW JERSEY.

DESIGN FOR A HOT-WATER BOTTLE OR SIMILAR ARTICLE.

Application filed June 7, 1928. Serial No. 27,035. Term of patent 7 years.

To all whom it may concern:

Be it known that I, STEPHEN L. PALMER, a citizen of the United States, and resident of the town of Teaneck, in the county of Bergen and State of New Jersey, have invented a new, original, and ornamental Design for Hot-Water Bottle or Similar Article, of which the following is a specification, reference being had to the accompanying drawing, forming part thereof.

Figure 1 is a top plan view, and Figure 2 is a side elevation of a hot water bottle or similar article.

I claim:

The ornamental design for a hot water bottle, or similar article, as shown.

STEPHEN L. PALMER.
